ABSTRACT OF THE DISCLOSURE

One winding on a television transformer core serves a high voltage filament lead. In order to shield the high voltage filament lead winding from a pulse winding also wound on the core, the filament winding is placed inside a molded insulating unit. The insulating unit has a single and double skirted portion. The double skirted portion has an opening to provide access for the filament lead winding.

BACKGROUND OF INVENTION

Field of invention

This invention relates to a new and improved combination sweep transformer and high voltage power supply assembly for television receivers having a new insulating shielding member for the high voltage filament lead.

More particularly, the invention relates to an integral, insulating shielding member which surrounds the core of a television receiver horizontal sweep transformer and serves as a coil mount for the turns of the high voltage filament lead. The insulating shielding member is designed so as to facilitate quick and easy assembly of the turns of the high voltage filament lead thereon while providing effective and safe shielding of the high voltage filament lead from other portions of the television receiver including grounded shields, etc.

Prior art problem

In the manufacture of commercial home television receiver sets, it is the practice to mount the high voltage filament lead of a high voltage rectifier tube employed in the high voltage power supply of the receiver on the core of the horizontal sweep transformer. By this expedient it is possible to avoid the necessity of separate, expensive, bulky and heavy core structures for both the sweep transformer and the high voltage power supply.

One of the problems that arises as a result of the above briefly mentioned design arrangement is that breakdown and arc-over is likely to occur between the high voltage filament lead and some of the other parts of the receiver, such as the grounded shielding structure normally employed to shield the high voltage power supply as a safety measure. Due to the close proximity of the parts of the combination sweep transformer and high voltage power supply assembly, it is difficult to avoid such breakdowns, arc-overs, short circuits, and the like. One of the known designs for overcoming this problem employs a set of three wound paper insulating tubes to provide the necessary shielding between the several parts of the assembly. Such an arrangement necessarily involves relatively complex manufacturing procedures requiring proper alignment of the three wound paper insulating tubes and the other parts of the combination sweep transformer and high voltage power supply assembly. The use of such components and procedures of course increases the manufacturing cost of the assembly. Further, it has been determined that under certain conditions the shielding provided by such a three-paper tube arrangement is inadequate and that breakdown or arc-over will occur. In other known arrangements where the shielding provided is adequate to prevent breakdown and arc-over, the manufacturing techniques and requirements for assembly are so demanding that only highly skilled personnel or expensive machinery can accomplish assemblage of the components. To overcome these problems, the present invention was devised.

2

It is therefore a primary object of the present invention to provide a new and improved combination television sweep transformer and high voltage power supply assembly for use in commercial home television receiving sets which employs a new and improved insulating shielding member for the high voltage filament lead, is readily assembled, and provides safe, effective shielding against breakdown and arc-over during operation.

Another object of the invention is to provide a new and improved insulating shielding member for use in combination television sweep transformer and high voltage power supply assemblies which is of unitary, molded, flexible construction, relatively inexpensive to manufacture, easy to assemble with other elements into a desired assembled relationship, and which provides effective and safe shielding of the high voltage filament lead.

In practicing the invention, a combination television sweep transformer and high voltage power supply assembly is provided which includes a core member and a high voltage filament lead having at least one turn wound around the core member and supported on an insulating unit surrounding the core member. The insulating unit comprises an integral, insulating body member having a single skirted portion comprised by a single layer of insulating material surrounding the core member and adapted to have a sweep transformer winding wound thereon. The integral insulating body member further includes a double skirted portion comprised by a pair of spaced-apart inner and outer insulating layers joined together by a flange portion with the single skirted portion being joined to the double skirted portion at the flange portion, and being in substantial axial alignment with the inner insulating layer of the double skirted portion. The outer insulating layer of the double skirted portion has a relatively narrow, axially extending access opening formed therein to provide ready access for the turns of the high voltage filament lead to the space between the inner and outer insulating layers.

The insulating unit preferably is formed of an integral, molded unit of thermoplastic material, such as polypropylene, with at least the outer insulating layer being flexible so as to facilitate winding of the turns of the high voltage filament lead in the space provided between the outer and inner layers of the double skirted portion. The end of the double skirted portion of the integral, molded insulating unit opposite the flange portion thereof is open-ended and extends beyond the turns of the high voltage filament lead a substantial distance so as to shield effectively the turns of the high voltage filament lead. The integral, molded insulating unit preferably is generally cylindrically-shaped and includes an annular reinforcing ridge portion adjacent the flange portion at the juncture of the single skirted portion with the double skirted portion.

BRIEF DESCRIPTION OF DRAWINGS

Other objects, features and many of the attendant advantages of this invention will be appreciated more readily as the same becomes better understood by reference to the following detailed description, when considered in connection with the accompanying drawings, wherein like

parts in each of the several figures are identified by the same reference character, and wherein:

FIGURE 1 is a side view of a prior art combination sweep transformer and high voltage power supply assembly which employs three wound paper tubes to provide shielding between the high voltage filament lead and other portions of the assembly;

FIGURE 2 is a partially broken away side view of a combination sweep transformer and high voltage power supply assembly constructed in accordance with the invention, and employing a new and improved integral, molded insulating shielding member constructed in accordance with the invention;

FIGURE 3 is an end view of the new and improved insulating shielding member constructed in accordance with the invention.

DETAILED DESCRIPTION OF PREFERRED EMBODIMENT

FIGURE 1 is a side view of a prior art combination sweep transformer and high voltage power supply assembly which employs three wound paper tubing insulating members shown at 11, 12 and 13 with the paper tubing or paper coil form 13 surrounding a cylindrical-shaped core member 14. The cylindrically-shaped core member 14 may comprise the C-core structure of a horizontal sweep transformer used in a commercial home television receiving set. For this purpose, a pulse winding shown at 15 is wound around the paper coil form 13. As is now well known in the art, the core member 14 also is employed as the core of a high voltage transformer comprised in part by a high voltage filament lead shown at 16 and also wound around the paper coil form 13 at a point spaced from the pulse winding 15. In order to properly shield and isolate the high voltage filament lead 16, the wound paper tubing members 11 and 12 are disposed on opposite sides of lead 16. In order to maintain or secure the turns of the high voltage filament lead 16 in place on the structure thus assembled, a band of elastic neoprene tubing shown at 17 is secured over the ends of the lead 16 in the manner shown in FIGURE 1.

From the above description, it will be appreciated that during assembly of the structure shown in FIGURE 1, it is necessary to first slide the paper coil form 13 into position, then in the proper order insert the paper tubing 11 and 12, separately wind the pulse winding 15 and the high voltage filament lead 16 after first threading the leads through the neoprene tubing 17. All of these requirements unduly complicate the construction of the assembly and consequently increase its cost, and require somewhat skilled labor. In addition, during operation, under certain kinds of atmospheric conditions, the possibility of breakdown or arc-over between the high voltage filament lead 16 and a grounded shielding structure normally enclosing the assembly shown in FIGURE 1, can occur. To overcome all of these problems, the assembly shown in FIGURE 2 was devised.

FIGURE 2 is a partially broken away side view of a new and improved combination television sweep transformer and high voltage power supply assembly constructed in accordance with the invention. The assembly shown in FIGURE 2 is comprised by a core member 14 and high voltage filament lead 16 having at least one turn but preferably a multiplicity of turns wound around the core member and supported on a single, integral, insulating shielding unit which surrounds the core member 14 and serves as a coil mount for both the high voltage filament lead 16 and the turns of a sweep transformer winding shown at 15. The insulating unit is comprised by an integral, molded insulating body member of polypropylene which has a single skirted portion 21 surrounding the core member 14 and having the sweep transformer winding 15 wound thereon. The integral insulating unit further includes a double skirted portion 22 comprised by a spaced-apart inner insulating layer 23 and outer insulating layer

24 which are joined together by a flange portion 25. The single skirted portion 21 is joined to and integral with the double skirted portion 22 at the flange portion 25 and is in substantial axial alignment with the inner insulating layer 23. The outer insulating layer 24 has a relatively narrow, axially extending access opening 26 formed therein to provide ready access for the turns of the high voltage filament lead 16 into the space between the inner and outer insulating layers 23 and 24. As stated previously, the integral, insulating unit is an integral molded unit of plastic material such as polypropylene with at least the outer insulating layer 24 being sufficiently thin and fabricated in a manner such that it is flexible so as to facilitate winding of the turns of the high voltage filament lead 16 in the space provided between the inner and outer layers 23 and 24, respectively.

As is best shown in FIGURE 2, the end of the double skirted portion 22 of the integral insulating unit opposite the flange portion 25 thereof, is open-ended and extends beyond the turns of the high voltage filament lead 16 a considerable distance so as to substantially surround the turns of the high voltage filament lead and to shield them effectively. In order to retain the turns of the high voltage filament lead 16 in the space between the inner and outer insulating layers 23 and 24, respectively, the insulating unit further includes at least one holding tab shown at 27 in FIGURE 3. The holding tab 27 is formed on the open end of the double skirted portion 22 and extends inwardly into the space between the inner and outer layers 23 and 24, respectively, for retaining the turns of the high voltage filament lead in the space.

As is best seen in both FIGURES 2 and 3 considered together, the relatively narrow access opening 26 in the outer insulating layer 24 extends axially and is formed in an offset housing part 28 that extends the full length of the double skirted portion 22 with the access opening 26 being formed with a generally T-shaped configuration. This T-shaped configuration for the access opening is arranged so that the enlarged crossed head of the T-shaped opening is located adjacent the flange portion 25 in a manner such that the high voltage filament lead 16 may be readily inserted and slipped through the relatively narrow throat portion of opening 26, wound into place around the inner insulating layer 23, held there by tab 27, and restrained from unwinding by the sides of the enlarged T-shaped head of the opening which also allows the separate ends of the high voltage filament lead 16 to extend in different directions. Thus, it will be appreciated that the shape of the opening 26 greatly facilitates assembly of the turns of the high voltage filament lead 16 on the shielding insulating body member and yet the construction of the body member is such that substantial shielding of the turns of the high voltage filament lead, is provided.

From a consideration of FIGURES 2 and 3 of the drawings, it will be appreciated that the specific embodiment of the invention disclosed is generally cylindrical in shape and preferably includes an annular reinforcing ridge portion 29 which is disposed adjacent the flange portion 25 at the juncture of the single skirted portion 21 with the double skirted portion 22. The provision of such an annular reinforcing ridge portion provides additional strength to the unit which enables it to physically withstand the rigors of the winding operation to which it is subjected, and further improves the electrical shielding characteristics between the turns of the high voltage filament lead 16 and the turns of the sweep transformer 15.

From the foregoing description, it will be appreciated that the invention makes available a new and improved combination sweep transformer and high voltage power supply assembly having a new single polypropylene insulating shielding unit which can be easily injection molded and whose flexible characteristics (at least on the double skirted portion thereof that supports the high voltage filament lead) allows easy insertion during manufacturing and provides a fixed lead location. During operation of such an assembly, the high voltage filament lead nor-

mally will be subjected to voltages in the neighborhood of 25 kilovolts; but in the event of a failure somewhere in the power supply circuit, this voltage can go up to about 35 kilovolts. Even under these conditions, as well as adverse environmental conditions such as high moisture content (high relative humidity) of the environment in which the assembly is used, the high voltage filament lead is effectively and safely shielded so that breakdown and arc-over from the high voltage filament winding to the sweep transformer windings or to a grounded shield structure, is avoided.

It will be appreciated, therefore, that the invention provides a new and improved combination television sweep transformer and high voltage power supply assembly for use in commercial home television receiving sets and which employs an improved insulating shielding member for the high voltage filament lead, is readily assembled, and provides safe and effective shielding against breakdown and arc-over during operation. The new and improved insulating shielding member is of unitary, molded, flexible construction, relatively inexpensive to manufacture, easy to assemble with other elements into a desired assembled structure, and provides effective and safe shielding of the high voltage filament lead which it supports.

Having described one embodiment of a new and improved combination television sweep transformer and high voltage power supply assembly and insulating shielding member therefor constructed in accordance with the invention, it is believed obvious that other modifications and variations of the invention are possible in the light of the above teachings. It is therefore to be understood that changes may be made in the particular embodiment of the invention described which are within the full intended scope of the invention as defined by the appended claims.

What is claimed is:

1. A combination television sweep transformer and high voltage power supply assembly including a core member and a high voltage filament lead having at least one turn wound around the core member and supported on an insulating unit surrounding the core member, the insulating unit comprising an integral insulating body member having a single skirted portion comprised by a single layer of insulating material surrounding the core member and adapted to have a sweep transformer winding wound thereon, and a double skirted portion comprised by a pair of spaced-apart inner and outer insulating layers joined together by a flange portion with the single skirted portion being joined to the double skirted portion at the flange portion and being in substantial axial alignment with the inner insulating layer of the double skirted portion, the outer insulating layer of the double skirted portion having a relatively narrow access opening formed therein to provide access for the turns of the high voltage filament lead to the space between the inner and outer insulating layers.

2. A television sweep transformer and high voltage power supply assembly according to claim 1 wherein the insulating unit is an integral molded unit of thermoplastic material with at least the outer insulating layer being flexible so as to facilitate winding of the turns of the high voltage filament lead in the space provided between the outer and inner layers of the double skirted portion.

3. A television sweep transformer and high voltage power supply assembly according to claim 1 wherein the end of the double skirted portion of the insulating unit opposite the flange portion thereof is open-ended and extends beyond the turns of the high voltage filament lead a substantial distance so as to shield effectively the turns of the high voltage filament lead, and wherein the insulating unit further includes at least one holding tab formed on the open end of the double skirted portion thereof and extending inwardly into the space between the inner and outer layers for retaining the turns of the high voltage filament lead in the space.

4. A television sweep transformer and high voltage power supply assembly according to claim 1 wherein the relatively narrow access opening in the outer insulating

layer of the insulating unit double skirted portion extends axially and is formed in an offset housing part of the double skirted portion with a generally T-shape and with the crossed head of the T-shape opening located adjacent the flange portion whereby assembly of the turns of the high voltage filament lead in the space between the inner and outer insulating layers of the double skirted portion is greatly facilitated.

5. A television sweep transformer and high voltage power supply assembly according to claim 1 wherein the insulating unit is generally cylindrically-shaped and includes an annular reinforcing ridge portion adjacent the flange portion at the juncture of the single skirted portion with the double skirted portion.

6. A television sweep transformer and high voltage power supply assembly according to claim 2 wherein the end of the double skirted portion of the insulating unit opposite the flange portion thereof is open-ended and extends beyond the turns of the high voltage filament lead a substantial distance so as to shield effectively the turns of the high voltage filament lead, the insulating unit further includes at least one holding tab formed on the open end of the double skirted portion thereof and extending inwardly into the space between the inner and outer layers for retaining the turns of the high voltage filament lead in the space, the relatively narrow access opening in the outer insulating layer of the insulating unit double skirted portion extends axially and is formed in an offset housing part of the double skirted portion with a generally T-shape and with the crossed head of the T-shape opening located adjacent the flange portion whereby assembly of the turns of the high voltage filament lead in the space between the inner and outer insulating layers of the double skirted portion is greatly facilitated, and the insulating unit is generally cylindrically-shaped and includes an annular reinforcing ridge portion adjacent the flange portion at the juncture of the single skirted portion with the double skirted portion.

7. An insulating unit for a combination television sweep transformer and high voltage power supply assembly comprising an integral insulating body member having a single skirted portion formed by a single layer of insulating material and adapted to surround a television sweep transformer core member and to have a sweep transformer winding wound thereon, and a double skirted portion comprised by a pair of spaced-apart inner and outer insulating layers joined together by a flange portion with the single skirted portion being joined to the double skirted portion at the flange portion and being in substantial axial alignment with the inner insulating layer of the double skirted portion, the outer insulating layer of the double skirted portion having a relatively narrow access opening formed therein to provide access for the turns of a high voltage filament lead to the space between the inner and outer insulating layers.

8. An insulating unit according to claim 7 wherein the insulating unit is an integral molded unit of polypropylene with at least the outer insulating layer being flexible so as to facilitate winding of the turns of a high voltage filament lead in the space provided between the outer and inner layers of the double skirted portion.

9. An insulating unit according to claim 7 wherein the end of the double skirted portion of the insulating unit opposite the flange portion thereof is open-ended and extends beyond the turns of a high voltage filament lead wound therein a substantial distance so as to shield effectively the turns of the high voltage filament lead, and includes at least one holding tab formed on the open end thereof and extending inwardly into the space between the inner and outer layers for retaining the turns of the high voltage filament lead in the space.

10. An insulating unit according to claim 7 wherein the relatively narrow access opening in the outer insulating layer of the insulating unit double skirted portion extends axially and is formed in an offset housing part of

the double skirted portion with a generally T-shape and with the crossed head of the T-shape opening located adjacent the flange portion whereby assembly of the turns of a high voltage filament lead in the space between the inner and outer insulating layers of the double skirted portion is greatly facilitated.

11. An insulating unit according to claim 7 wherein the insulating unit is generally cylindrically-shaped and includes an annular reinforcing ridge portion adjacent the flange portion at the juncture of the single skirted portion with the double skirted portion.

12. An insulating unit according to claim 7 wherein the insulating unit is an integral molded unit of polypropylene with at least the outer insulating layer being flexible so as to facilitate winding of the turns of a high voltage filament lead in the space provided between the outer and inner layers of the double skirted portion, the end of the double skirted portion of the insulating unit opposite the flange portion thereof is open-ended and extends beyond the turns of a high voltage filament lead wound therein a substantial distance so as to effectively shield the turns of the high voltage filament lead, at least one holding tab is formed on the open end of the double skirted portion and extends inwardly into the space between the inner and outer layers for retaining the turns

of the high voltage filament lead in the space, the relatively narrow access opening in the outer insulating layer of the insulating unit double skirted portion extends axially and is formed in an offset housing part of the double shielded portion with a generally T-shape and with the crossed head of the T-shape opening located adjacent the flange portion whereby assembly of the turns of a high voltage filament lead in the space between the inner and outer insulating layers of the double skirted portion is greatly facilitated, and the insulating unit is generally cylindrically-shaped and includes an annular reinforcing ridge portion adjacent the flange portion at the juncture of the single skirted portion with the double skirted portion.
